UNITED STATES PATENT OFFICE.

ANDREW NILSON, OF CHICAGO, ILLINOIS, ASSIGNOR TO NILSON BROS., OF CHICAGO, ILLINOIS, A CORPORATION OF ILLINOIS.

TOOL-MOUNTING.

1,266,520.

Specification of Letters Patent. Patented May 14, 1918.

Application filed January 15, 1917. Serial No. 142,422.

To all whom it may concern:

Be it known that I, ANDREW NILSON, a citizen of the United States, residing at Chicago, in the county of Cook and State of Illinois, have invented a certain new and useful Improvement in Tool-Mountings, of which the following is a full, clear, concise, and exact description, reference being had to the accompanying drawings, forming a part of this specification.

My invention relates to tool mountings and has for its object the provision of an improved structure whereby a drill or similar device may be accurately held in place for properly preparing furnaces or similar structures to receive tubes.

In my application Serial No. 143,228, filed Jan. 19, 1917, I show a furnace structure in which it is necessary to connect and mount a water carrying tube between the water legs of a boiler. In order to mount this tube properly so that it may have an accurately predetermined position, it is necessary that the holes passing through the water legs upon opposite sides of the furnace accurately register. If such accurate registration is not effected it is difficult and frequently impossible to properly aline the tube in order to have it securely expanded in place.

My invention concerns itself with a structure for positioning a drill so that it may be used by workman more or less unfamiliar with accurate measurements in such a manner that holes in the opposite water legs of boilers may accurately register.

I will explain my invention more in detail by referring to the accompanying drawing, in which—

Figure 1 is a transverse sectional view of a furnace with my improved device in position ready for drilling;

Fig. 2 is a fragmentary top view thereof; Fig. 3 is a perspective view showing my improved mounting structure, together with the tool in place thereon, and

Fig. 4 is a fragmentary sectional view of one of the jacks for alining the structure.

Referring more particularly to Fig. 1, a furnace 10 is shown having the water legs 11 and 12, these water legs having respectively the walls 13, 14, 15 and 16. In order to adapt this furnace so that a baffle wall or arch may be properly supported it is necessary to have a water carrying tube ex-

tend between the water legs 11 and 12. In order to do this properly it is necessary to drill three holes, which holes are accurately alined, these holes being respectively through the walls 14, 15 and 16. Then the tube may project from the exterior through the walls 15 and 16 and have its extremity expanded against the opening in the wall 14. The tube may then also be expanded to close the apertures drilled in the walls 15 and 16.

In order to secure the accurate alinement of these holes I have provided a mounting structure, which mounting structure carries a drilling device which in this instance is shown as an electric drill 17. The mounting structure in its preferred form comprises a suitable structure 18 upon which cross pieces 19, 19 are mounted. Upon these cross pieces a bar 20 is preferably fixedly secured. This bar is accurately alined in a horizontal position through the agency of the jacks 21. These jacks are shown more in detail in Fig. 4 where the top of the jack is mounted in a seat 22 and the screw 80 threaded portion of the jack engages the flanged screw threaded shell 23. A plate 24 is likewise interposed between the jacks and the cross pieces 19, this plate carrying the shells 23 as readily apparent from the illustration. The plate 20 carries a vertical shelf 25 on the upper surface of which a roller 26 carried by the framework of the drill rolls. The plate 20 also carries a track 27. This track is preferably U-shaped as shown. The framework of the drill likewise has mounted thereon a pair of rails 28, which rails are equidistant from the axial line of the drilling tool 29. These rails are securely mounted to the framework of the drill 17, being thus symmetrical with respect to the drilling tool 29. Thus whether the drill is turned over through an angle of 180° so that the drill tool points toward the left, this drilling tool is always in the same straight line. Under these conditions

holes can be drilled in the opposite walls 14, 15, respectively which are in accurate alinement. Suitable means are of course provided to exert pressure upon the drill structure as the drilling tool is rotating, and these means preferably include the adjusting screw 30 and the adjusting back 31.

From what has been thus described it will be readily apparent to those skilled in

the art that my improved tool mounting permits me to accurately aline holes for the reception of a tube. Changes may of course be made in the structure and arrangement 5 and the invention applied to a multitude of uses within the scope of the appended claims.

Having however thus described one form which my invention may take, what I claim 10 10 as new and desire to secure by Letters Patent is:

1. In a structure of the character described the combination with an operating tool and its framework, of a support for 15 said tool framework upon which said tool framework is adapted for motion to and fro, a guide upon said support, and means carried by said tool framework symmetrically arranged with respect to the axis of 20 said operating tool adapted interchangeably to engage said guide whereby said tool and framework may be accurately alined to operate in opposite directions.

2. In a structure of the character described the combination with an operating tool and its framework, of a support for 25 said tool framework upon which said tool framework is adapted for motion to and fro, a guide upon said support, and a pair 30 of rails carried by said tool framework symmetrically arranged with respect to the axis of said operating tool adapted interchangeably to engage said guide whereby said tool and framework may be accurately alined 35 to operate in opposite directions.

3. In a structure of the character described the combination with an operating tool and its framework, of a support for 40 said tool framework upon which said tool framework is adapted for motion to and fro, a guide upon said support, and means carried by said tool framework symmetrically arranged with respect to the axis of 45 said operating tool adapted interchangeably to engage said guide whereby said tool and framework may be accurately alined to operate in opposite directions, and means for leveling said support.

4. In a structure of the character described the combination with an operating tool and its framework, of a support for 50 said tool framework upon which said tool framework is adapted for motion to and fro, a guide upon said support, a pair 55 of rails carried by said tool framework symmetrically arranged with respect to the axis of said operating tool adapted interchangeably to engage said guide whereby said tool and framework may be accurately alined 60 to operate in opposite directions, and means for leveling said support.

5. In a structure of the character described the combination with an operating tool and its framework, of a support for 65 said tool framework upon which said tool framework is adapted for motion to and fro, a guide upon said support, means carried by said tool framework symmetrically arranged with respect to the axis of 70 said operating tool adapted interchangeably to engage said guide whereby said tool and framework may be accurately alined to operate in opposite directions, means for leveling said support, a shelf carried by 75 said support, and a roller coöperating with said shelf carried by said tool framework.

6. In a structure of the character described the combination with an operating tool and its framework, of a support for 80 said tool framework upon which said tool framework is adapted for motion to and fro, a guide upon said support, a pair of rails carried by said tool framework symmetrically arranged with respect to the axis 85 of said operating tool adapted interchangeably to engage said guide whereby said tool and framework may be accurately alined to operate in opposite directions, means for leveling said support, a shelf carried by said support, and a roller coöperating with said 90 shelf carried by said tool framework.

7. In a structure of the character described the combination with an operating tool and its framework, said tool and its framework being adapted for operation 95 upon work in opposite directions, of a support for said tool framework on which said tool framework is adapted for motion to and fro both in a given direction and in the reverse direction, and guide means interposed between said framework and said support whereby said tool and framework are accurately alined to operate in opposite directions.

8. In a structure of the character described the combination with an operating tool and its framework, of a support for 105 said tool framework upon which said tool framework is adapted for motion to and fro, a guide upon said support, and means carried by said tool framework adapted alternately to engage said guide whereby said tool and framework may be accurately alined 110 to operate in opposite directions.

In witness whereof, I hereunto subscribe 115 my name this 16th day of December, A. D. 1916.

ANDREW NILSON.
